ELECTRIC SWITCH

Martin F. Koenig, Milwaukee, Wis., assignor to
Cutler-Hammer, Inc., Milwaukee, Wis., a corporation of Delaware

Application January 10, 1946, Serial No. 640,297

29 Claims. (Cl. 206—16)

1

This invention relates to improvements in electric switches. Although not limited thereto, the invention is especially advantageous when embodied in a switch of the multipole type.

A primary object of the invention is to normally prevent welding of the contacts when handling an inrush load, such as a motor load, and to positively insure separation of the contacts at will, in the event of welding or "freezing" of any of the same.

Another and more specific object is to provide a mechanical kick-off device adapted, in the double-throw form of the switch, to insure disengagement of all contactors from one set of their associated stationary contacts before the operating lever and the sliding block reach their center or "off" position, whereby simultaneous completion of circuit connections at both sides of the switch is positively prevented.

Another object is to minimize the tendency of the contactors to bounce or rebound when closing, to correspondingly decrease the likelihood of the same welding or sticking to their cooperating stationary contacts.

Another object is to so construct the insulating base of the switch and the slider block as to provide a completely enclosed compartment for each pole of the switch, whereby the current controlling capacity of the switch is greatly increased over prior art switches of corresponding size.

Another object is to provide means for properly positioning the slider block with respect to the insulating base as an incident to given degrees of movement of the operating lever in opposite directions respectively.

Another object is to provide a plural form of positioning means to afford manual operation of the switch to open or closed position, in the event of failure of a part of the positioning means.

Another object is to provide for attainment of the aforementioned desirable results without in anywise decreasing the normal relatively long life of the switch.

Another object is to provide switches having the aforementioned desirable features, while avoiding any increase in the outside dimensions thereof as compared with prior art switches which the same are adapted to supersede.

Another object is to provide novel and simple means to render a switch of the aforementioned character of the momentary contact type in one or two of its respective positions.

Other objects and advantages of the invention will hereinafter appear.

The accompanying drawings illustrate certain

2

preferred embodiments of the invention which will now be described, it being understood that the invention is susceptible of embodiment in other forms within the scope of the appended claims.

In the drawings,

Figure 1 is a top plan view of a recessed molded insulating base adapted for use in constructing a double-throw switch of the three-pole type.

Fig. 2 is a vertical longitudinal section, on the line 2—2 of Fig. 1, but with the contactor-carrying slider block and the operating and supporting superstructure in assembled position.

Fig. 3 is a transverse vertical sectional view, on the line 3—3 of Fig. 1, but showing all of the switch parts in assembled relation, as in Fig. 2.

Fig. 4 is a horizontal sectional view, looking in the direction of the arrows 4—4 in Fig. 3.

Fig. 5 is a bottom plan view of the switch base shown in Fig. 1, illustrating the form and arrangement of the terminal elements of the binding screw type.

Fig. 6 is a top plan view of a modified form of recessed molded insulating base, which is so formed and combined with stationary contact members as to provide a three-pole switch of the single throw "on" and "off" type.

Fig. 7 is a vertical sectional view, on the line 7—7 of Fig. 6, but with the contactor-carrying slider block and the operating and supporting superstructure in position.

Fig. 8 is a bottom plan view of the complete switch shown in Fig. 7, showing the form and arrangement of the solder lug type of wiring terminal members.

Fig. 9 is a horizontal sectional view, on the line 9—9 of Fig. 7, showing in top plan the contactor-carrying slider block in the circuit-completing position thereof, and showing (partly in dotted lines) the spring-biased positioning means associated therewith, and

Fig. 10 is a top plan view of a further modified form of recessed molded insulating base, quite similar to that shown in Fig. 1, but having the recess walls thereof notched in the manner shown in Figs. 6 and 9, to provide a so-called double-throw switch without an intermediate "off" position.

Referring first to that form of my invention shown in Figs. 1 to 5, inclusive, the numeral 15 designates an insulating base molded from any suitable insulating material, such as "Bakelite." Base 15 is provided with a relatively large substantially rectangular recess 16 opening to the upper surface 17 thereof (see Fig. 1). As shown

in Figs. 1 and 3, a pair of relatively wide barrier portions 18 and 19 are formed integrally with the bottom wall 20 of recess 16 and extend longitudinally of the latter. Barrier portions 21 and 22, of the same height as portions 18 and 19, are formed integrally with and extend longitudinally of the bottom and side walls of recess 16. Formed integrally with portions 18 and 19 are additional barrier portions, which respectively comprise relatively low intermediate portions 23 and 24, and pairs of opposite end portions 25, 26 and 27, 28. As indicated in Fig. 1, the pairs of barrier portions 25, 26 and 27, 28 are of substantially rectangular contour, and the same extend upwardly to a plane flush with the upper surface 17 of base 15, for a purpose hereinafter described. The barrier portions aforementioned are so spaced and arranged as to provide within recess 16 three substantially identical compartments extending in parallel relationship to each other longitudinally of base 15, as best illustrated in Fig. 1.

As shown in Figs. 1 and 2, the bottom wall portions of the three parallel compartments are provided with transversely extending pairs of barriers 29, 30; 31, 32 and 33, 34, respectively; the form thereof in cross section being illustrated in Fig. 2. Each compartment is thus divided into a relatively long intermediate portion and relatively shorter opposite end portions. The three portions of each compartment are respectively provided with circular openings (see Fig. 2) to accommodate the shanks of a corresponding number of rivets 35. The head of the intermediate rivet 35 of each group underlies and clamps in position the horizontal arm of an L-shaped, punched and stamped sheet metal wiring terminal member 36; the downwardly extending arm of which is tapped to receive the shank of a wiring terminal screw 37. Said horizontal arms of terminal members 36 are preferably positioned, as shown in Figs. 3 and 5, within a groove 38 extending transversely of the lower surface of base 15; said groove 38 having barriers 39 and 40 formed integrally with the walls thereof to separate said terminal members from each other. The vertical portions of terminal members 36 are preferably positioned as shown in Figs. 3 and 5, and after the riveting operation the vertical arm of the middle terminal member is bent at an angle to the vertical, as indicated at 30°, to insure satisfactory mechanical and electrical clearance between the respective binding screws 37.

The hollow upper ends of the middle rivets 35 penetrate openings in the flat rectangular central portions of a group of resilient contact members 41 of good electrical conductivity; each member 41 having oppositely extending upwardly angled and outwardly and downwardly curved ends 41a, 41b which are adapted for continuous engagement jointly with the movable contactors 42 hereinafter described. The hollow shanks of said rivets are upset over said central portions of contact members 41, as shown in Figs. 1 to 3, to retain the associated parts in assembled relation to base 15.

The outer rivets 35 of each group penetrate aligned openings in the flat terminal members 43, in the end portions of the aforementioned compartments, and in the horizontal portions of a corresponding number of L-shaped stationary contacts 44; the vertical portions of contacts 44 being oppositely arranged, as shown in Figs. 1, 2 and 4 adjacent the end walls of the respective compartments, and each vertical portion having

5 a contact tip 46a rigidly attached thereto in any suitable manner, as by spot-welding. Contact tips 46a are preferably of circular or disk-shape, and are molded from a suitable powder composition, such as a silver base composition.

As shown in Figs. 2 and 4, the shanks of the binding screws 37 associated with terminal members 43 are adapted to be accommodated in a corresponding number of recesses 45a which open 10 to the bottom and end surfaces of base 15.

The three contactors 42 each have a relatively long horizontal portion and relatively short ends 42a and 42b bent upwardly at right angles thereto. Contact tips 46a identical with the corresponding tips aforescribed, are respectively attached to the outer surfaces of the upturned ends 42a and 42b, for cooperation with the stationary contact tips of the switch. Contactors 42 are carried by a molded insulating block 48 (Figs. 2, 3 and 4) which is preferably of approximately rectangular contour. Block 48, which is preferably likewise composed of "Bakelite," has a length (transversely of base 15) to afford a rather close but free-sliding fit between the flat end surfaces thereof and the side walls of the aforementioned recess 16 in base 15 (see Fig. 4). The width of block 48 (Fig. 4) is such as to afford a predetermined degree of sliding movement of said block within the recess 16.

30 As shown in Figs. 2, 3 and 4, block 48 is provided at the ends thereof adjacent the sides of recess 16 with relatively narrow upward extensions 46 and 47 having flat upper surfaces. Said upper surfaces of extensions 46 and 47 are 35 adapted to slidably engage the lower surface of a flat punched insulating plate 48, which seats against the flat upper surface 17 of base 15. Base 15 is provided with ribs or projections 49 and 50 of rectangular form in cross section which 40 extend throughout the length of the sides, and slightly beyond the ends thereof (Figs. 1 and 5), and insulating plate 48 is positioned between said ribs. A flat punched sheet metal plate 51 is superimposed upon plate 48, and is of the same 45 peripheral contour as the latter; the plates 48 and 51 being jointly of the same height as extensions 46 and 47, as best illustrated in Fig. 3.

The metal plate 51 is provided with a centrally located circular opening to accommodate the reduced lower end of a metal bushing 52, which end is upset over the lower surface of plate 51 to secure said parts in assembled relation (Figs. 2 and 3), as shown at 52a. The inner peripheral walls of bushing 52 are preferably shaped as 55 shown in Fig. 2 to provide oscillatory clearance for the outwardly projecting manually operable portion 53a and the enlarged intermediate portion 53b of the operating lever of the switch; said enlarged portion 53b having an opening aligned with countersunk openings formed in bushing 52 to accommodate a pivot pin 54, whereby said lever is limited to oscillatory movement in a plane parallel to the length of base 15. The reduced lower portion 53c of said lever is provided with a partially spherical end 53d which fits into a cylindrical recess 55a formed centrally in the upper surface of block 48; a coiled compression spring 56 being interposed between the bottom wall of recess 55a and the end 53d of the lever. The upper end of recess 55a is flared outwardly as shown at 55b to insure proper clearance between the lever enlargement 53b and block 48.

The block 48 is provided in its lower surface 70 with three pairs of endwise aligned notches or

recesses (one pair of which are shown at 45^c and 45^d in Fig. 2) to accommodate pairs of like coiled compression springs 56, 56. Each pair of springs 56 acts in the intermediate or "off" position (not shown) of lever 53^a and block 45 to maintain their associated contactor 42 in a centered or symmetrical relationship to the block 45. The outer ends of the pairs of recesses 45^c and 45^d are enlarged, as shown in Fig. 2, to provide a predetermined degree of lost motion between the upturned ends 42^a and 42^b of the respective contactors 42 and the block 45. Thus, upon movement of lever 53^a to the right-hand extreme position shown in Fig. 2, block 45 will be moved toward the left to effect engagement of each of the left-hand contactor tips 44 with the tips 44 of the left-hand stationary contacts; the left-hand springs 56 of the contactors being compressed and the right-hand springs 56 being permitted to correspondingly expand.

However, in order to maintain the proper degree of pressure of the contactor tips against the stationary contact tips in each extreme or "on" position of the switch, I prefer to provide the spring-biased positioning means best illustrated in Fig. 4. Said means consists (in the double-row type of switch) of a series of three vertical notches 15^a, 15^b and 15^c arranged in alinement on opposite side walls of recess 16. Said notches are of outwardly pointed substantially triangular form in transverse cross section, and the same open to the upper surface 17 of base 15. In practice the middle notches 15^b of each series are preferably slightly larger and deeper than the other two notches of the series.

Block 45 is provided centrally of its width and at the mid-point of its depth with alined outwardly opening cylindrical recesses 45^e and 45^f. Positioned within each of said recesses is an insulating plunger 57 having a slightly rounded substantially conical outer end to fit into the respective notches of the series associated therewith. Interposed between the end wall of a recess 45^e or 45^f and the inner end of each plunger 57, and held by the means illustrated in centered relationship to the latter, is a coiled compression spring 58, 58, whereby said plungers are biased outwardly from block 45 for cooperation jointly with the two series of notches aforementioned.

As shown in Fig. 3, the block 45 is provided in its lower surface with three relatively shallow grooves 60, 60 and 61 which partially overlie the horizontal portions of the respective contactors 42 to minimize friction between the latter and said block as an incident to the lost motion provided between said parts.

Block 45 is also provided in its lower surface with a pair of relatively deeper grooves 62 and 63 (Fig. 3) to accommodate the aforementioned projections or ribs 23 and 24 in the bottom wall of recess 16 to assist in rectilinearly guiding the latter within said recess; and more particularly to assist in providing a substantially completely closed compartment for each of the contactors 42 and its associated stationary contacts. Also for such purpose block 45 is provided at opposite ends thereof with pairs of vertical grooves or notches 64, 65 and 66, 67, to respectively accommodate the aforementioned barrier portions 27, 25 and 23, 26 (see Fig. 4) which extend flush with the upper surface 17 of base 15.

Upon assembly of the aforescribed parts as best illustrated in Figs. 2 and 3 the same may be retained in assembled relation by means of a combined cover and supporting member 68 (Figs.

2 and 3). Member 68 is punched and stamped from sheet metal to a width corresponding to the distance between the aforementioned projections 49 and 50 at the upper surface 17 of base 15, as best illustrated in Fig. 3; said member having horizontal portions 68^a and 68^b at opposite ends thereof which overlie and are adapted to clampingly engage the end portions of metal plate 51, whereby the latter similarly engages insulating plate 48, so that the latter is adapted to overlie the block 45 to prevent displacement of the latter above the upper surface 17 of base 15, while permitting sliding movement of said block to different positions within recess 16, as aforescribed.

Member 68 is provided with downwardly extending opposite end portions 68^c and 68^d (Fig. 2), the lower edges of which are located slightly above the plane of the upper end walls of the sets of three recesses 15^d at opposite ends of base 15 (Fig. 4). The lower edges of portions 68^c and 68^d are provided with pairs of lugs, each of which comprises an upper portion 68^e and a relatively narrower and readily bendable tongue portion 68^f which is bent so as to engage the upper end wall of the corresponding recess, as indicated in dotted lines in Fig. 2.

Member 68 is also provided with a flat portion 68^g which is offset upwardly to a substantial degree above the aforementioned portions 68^a and 68^b. Portion 68^g is provided with a centrally located circular opening to accommodate the aforementioned bushing 52; the plane of the former being preferably above the pivot pin 54, whereby the latter is concealed. Portion 68^g is also provided with a pair of downwardly extruded and tapped openings 68^h and 68ⁱ to take a pair of bolts or screws (not shown) whereby the switch as a whole may be attached in a substantially flush relationship to a panel or similar support.

As shown in Figs. 1 and 2, base 15 is preferably provided adjacent opposite ends thereof with centrally located cylindrical recesses 69 and 70 which open to the upper surface 17; thin integral diaphragms 69^a and 70^a being initially formed; which diaphragms may be broached out or otherwise removed to permit insertion of the shank of a headed rivet or the like (not shown) therethrough. As shown in Fig. 2, plates 51 and 68 are provided with openings alined with the respective recesses; and when such an alternative form of attachment of member 68 to base 15 is desired, the former would likewise be provided with openings alined with recesses 69 and 70. With such an arrangement the member 68 would preferably extend only to the outer edges of the aforementioned flat portions 68^a and 68^b; although, of course, the downwardly extending portions 68^c and 68^d and their associated lugs might be permitted to remain intact, to afford a more rigid type of securement.

It is to be understood that upon assembly of the switch parts as shown in Fig. 2, for instance, the block 45 will be depressed against the bias of the three pairs of spring contact arms 41^a, 41^b associated with the intermediate or common terminals 36 of the switch, whereby a predetermined degree of pressure of said pairs of arms against the respective contactors 42 is insured.

With the sliding block 45 in the left-hand circuit-completing position shown in Figs. 2, 3 and 4, the handle 53^a may be moved in a counter-clockwise direction toward its intermediate or vertical position; the lower end 53^d of the lever 53 acting to forcibly move block 45 toward the right

(Fig. 2). This reduces the degree of compression of the left-hand springs 56 against their respective contactors 42 to correspondingly decrease the degree of pressure of said contactors against the left-hand stationary contacts. Such movement of block 45 toward the right will be yieldably resisted by the action of spring-pressed plungers 57 (Figs. 3 and 4) against the right-hand walls of grooves or notches 15^a (Fig. 1), which act as cam surfaces. The arrangement is preferably such that the contactors 42 will be disengaged from the left-hand stationary contacts just prior to or at the instant when the ends of plungers 57 are riding over the cam peaks between the adjacent pairs of grooves 15^a and 15^b; so that normally the spring-pressed plungers 57 will act to complete the movement of block 45 (and consequently of handle 53^a) to the intermediate or "off" position, even though the manual pressure upon the handle 53^a may have been released. Such completion of the movement of block 45 to its intermediate position will, of course, be effected with a quick or snap action, whether or not the handle 53^a is manually releasable; a sufficient degree of lost motion being provided between the lower end 53^d of the lever and block 45 for this purpose. In such intermediate position of block 45 the pairs of springs 56 associated with each contactor 42 will act to center the same with respect to the block, so that the respective contactor tips 44^a will be substantially equally spaced from the tips 44^a of the opposite sets of stationary contacts.

If, during the aforescribed movement of block 45 from its left-hand extreme position toward its intermediate position, one or more of the contactors 42 should "freeze" or weld to its associated left-hand stationary contact, the adjacent shoulders formed on block 45 will engage the upper ends of the vertical arms 42^b of any sticking contactors to positively disengage or pry the left-hand ends thereof loose from such stationary contacts, thus breaking the freeze. Such mechanical kick-off action will, moreover, be effected before the block 45 and handle 53^a reach their intermediate "off" position. This feature is of great practical importance, inasmuch as I thereby insure against any possibility that the block 45 and any unfrozen contactor or contactors might be moved to their extreme right-hand position while another contactor remained frozen in its left-hand extreme position.

In normal operation of the switch from its intermediate position to its right-hand circuit-completing position, only counterclockwise movement of handle 53^a is necessary, the spring-pressed plungers 57 riding over the peaks between the pairs of adjacent grooves 15^b and 15^c acting at substantially the moment of engagement of the contactors with the right-hand contacts to provide the desired degree of contact pressure (through the medium of the right-hand springs 56). By reason of the "floating" or yieldable support of the contactors 42 by block 45 during endwise movement thereof into engagement with the stationary contacts, and by reason of the overpowering spring-bias thereof into engaging position afforded by plungers 57, bouncing of the contactors 42 when engaging the stationary contacts is effectively prevented. As aforeindicated, such bouncing of the contactors when closing is one of the main causes of freezing or welding thereof to the stationary contacts.

Although, as aforesated, all of the contactors 42 are compelled to move with block 45 to its in-

termidate "off" position; it is nevertheless possible to effect rapid movement of the contactors from either of the extreme positions thereof to the other, by merely manually moving or flipping the handle 53^a from one to the other of its extreme positions.

As will be apparent from the above description, when the switch parts are in the respective positions thereof shown in Fig. 2, each of the intermediate terminal members 36 will be electrically connected with the left-hand stationary contact respectively associated therewith. When slider block 45 is in its right-hand extreme position each intermediate terminal member will be electrically connected with its associated right-hand contact; and in the intermediate position of block 45 all of the circuit connections controlled by the switch will be interrupted.

By reason of the aforescribed slidable interlocking or overlapping arrangement of the grooves or slots in block 45 with respect to the barriers formed in the recess 16 in base 15, the contactors 42 and their cooperating stationary contacts are respectively housed in completely closed compartments, to effectively separate and insulate the poles of the switch from each other. This greatly increases the current controlling capacity of the switch and eliminates the possibility of arcing across the switch poles or to any grounded part of the switch.

Although I have illustrated my invention as applied to a three-pole switch, it will be apparent to those skilled in the art that the invention is applicable to switches having a greater or lesser number of poles than that illustrated.

As indicated at 71 in Figs. 2 and 5, each of the outer terminal members 43 has associated with the inner end portion thereof a pair of projections or bosses 71, 71, formed integrally with the bottom wall of base 15 to insure proper positioning of said members and to restrain the same against substantial lateral displacement.

As shown in Fig. 1 base 15 is provided in its upper surface with four symmetrically arranged trough-shaped grooves 72, 73, 74 and 75, whose inner ends open to the recess 16 in base 15; and block 45 (Fig. 4) is likewise provided with four grooves 76, 77, 78 and 79 of corresponding shape and size, the aligned pairs of which have their open ends aligned with the open ends of the aforementioned grooves 72 to 75, inclusive. The cooperating sets of grooves 72, 76; 73, 77; 74, 78 and 75, 79 are respectively adapted to accommodate coiled compression springs (not shown), so that if four of such springs are employed the block 45 will always be returned to its intermediate "off" position upon release of handle 53^a. That is to say, each pair of springs at one end of base 15 will apply sufficient force to block 45 to return it to its intermediate position, against the resistance offered to such movement of block 45 by the aforementioned spring-pressed plungers 57 thus affording the so-called momentary contact type of operation of the switch parts at that end of base 15. If a non-momentary contact type of operation of the switch parts is desired at the other end of base 15, the two springs at such end would, of course, be omitted. The aforementioned springs will be retained within the grooves into which they may be inserted by the insulating plate 48 overlying the same.

In Figs. 6 to 9, inclusive, I have illustrated a three-pole, single throw switch constructed in accordance with my invention. The molded insulating base 80 is in many respects, including

the overall dimensions thereof, identical with the base 15 aforescribed. The recess 81 in base 80 differs from the recess 16 in base 15 in respect of omitting the pairs of barriers of triangular form in transverse cross section from the three compartments formed in recess 81 by barrier portions like those aforescribed (see Figs. 6 and 7). As shown in Fig. 7, the three transversely aligned recesses 82 have thin integral diaphragms 83 formed at the lower ends thereof, to prevent entrance of dust or other foreign matter into recess 81. If desired, the die member employed to form recess 81 may be so shaped as to also eliminate such recesses 82.

Only three stationary contacts 44 (like those aforescribed) are required in this single throw switch; the same being shown positioned at the left-hand end of recess 81 (Figs. 6 and 7) to provide for "on" positioning of the switch parts upon clockwise movement of handle 84 of the operating lever; although said contacts 44 might be positioned at the other end of recess 81 if desired. Contacts 44 are here shown as having terminal members 85 attached thereto by rivets 35 and exposed at the lower surface of the base. Resilient contact members 86 (Figs. 6 and 7) are attached, at the other end of each of the three compartments, to terminals 85 by means of rivets 35 like those aforesigned. The sliding block 45 and the parts carried thereby are identical with such parts aforescribed, and the same have been given like characters of reference. However, the three contactors 42 have only one contact tip 44^a attached thereto; the same being located at the left-hand end thereof for cooperation with the tips 44^a carried by the stationary contacts 44; and, in addition, the right-hand springs 56 associated with the respective contactors 42 are omitted. The upwardly extending and downwardly curved free end portions of members 86 are adapted to continuously engage the lower surfaces of the horizontal portions of the respective contactors 42 (Fig. 7) to afford electrical connections between the latter and the right-hand terminal members 85. Inasmuch as the aforesigned right-hand springs 56 are omitted, it will be apparent that in the "off" position of the switch the contactors 42 will not be biased to a centered relationship to block 45. However, due to the greater degree of throw of block 45 in moving the contactors 42 from "on" to "off" position, an adequate spacing of contactors 42 from the contacts 44 is provided in said "off" position.

Recess 81 is further provided in the side walls thereof with opposed pairs of like grooves or slots 87, 87 and 88, 88, which are adapted for cooperation with the plungers 57 to bias block 45 and the contactors 42 carried thereby into one or the other of their extreme positions. As will be apparent from consideration of Figs. 9 and 4, blocks 45 are required to move like distances between opposite extreme positions in each form of switch; and hence the distance between the outer edges of grooves 87, 88 is substantially the same as the distance between the outer edges of the grooves 15^a and 15^c in the double-throw switch aforescribed.

The insulating base 80 and block 45 of Figs. 6 to 9 may have associated therewith the aforescribed supporting and operating superstructure shown in Figs. 2 and 3, including metal plate 51, bushing 52, lever 53^a and cover member 68. However, I have illustrated in Fig. 7 an alternative form of supporting and operating super-

structure, including a punched and stamped sheet metal cover member 89, which is preferably attached to base 80 in the same manner as the member 68 aforescribed. Member 89 is provided with a centrally located raised portion or bulge 90 of substantially rectangular contour; thus providing an upwardly offset horizontal portion 91 having a circular opening to accommodate the reduced lower end of an externally threaded hollow bushing 92, which reduced end is upset over the inner surface of portion 91, as indicated at 93, to rigidly secure said parts together. The aforementioned lever 84 has an enlarged portion 84^a which is perforated to accommodate the pivot pin 54, whose head and upset shank end (not shown) are accommodated within countersinks at opposite sides of bushing 92. Lever 84 is also provided with portions 84^b, 84^c and 84^d; the portion 84^d being adapted for engagement with the walls of recess 45^a in block 45, and the same being engaged by the upper end of spring 55 for the purpose aforescribed. Inasmuch as the bushing 92 of Fig. 7 is attached to cover member 89, the metal plate 51 of Fig. 2 is not required.

It is to be understood that either the binding screw type of terminals shown in Figs. 2, 3 and 5 or the solder lug type of terminals shown in Figs. 7 and 8 may be employed with both of the insulating bases 15 and 80 aforescribed.

In Fig. 9 I have shown diagrammatically a pair of coiled compression springs 94, 94 located with the complementary pairs of grooves 72, 76 and 75, 79; said springs being of sufficient strength to normally bias block 45 to its right-hand extreme or "off" position upon manual release of lever 84, notwithstanding the bias afforded by spring-pressed plungers 57, 57 in the left-hand extreme position of block 45. If desired, the springs 94, 94 might be transposed to the complementary sets of grooves 73, 77 and 74, 78, to provide a single throw switch of the momentary "off" type.

In Fig. 10 I have illustrated a further modified form of switch, which is a hybrid, in that the base 80 of Figs. 6 to 9 may be employed in conjunction with three stationary contacts in each of the three compartments, such contacts being shown as identical with those of the switch of Figs. 1 to 5 and being designated by corresponding numerals of reference. In constructing a switch like that illustrated in Fig. 10 the base 80 has the three diaphragms 83 (of Fig. 7) at the lower ends of openings 82 broached out to accommodate the shanks of the rivets utilized for attaching the double-armed resilient stationary contacts 41. A slider block like the block 45 aforescribed will be employed with the base 80 of Fig. 10, such slider block having three contactors associated therewith, and each contactor having a pair of coiled compression springs associated therewith, in the manner indicated at 56, 56 in Fig. 1. When all of the other switch parts are assembled with the base 80 of Fig. 10, a so-called double-throw switch without an "off" position will be provided; it being understood that the alternative forms of supporting and operating superstructures aforescribed may be employed with the base 80 of Fig. 10.

I claim:

1. In a multi-pole electric switch, in combination, a recessed molded insulating base, a molded insulating block slidably positioned within said recess for movement from one extreme position to the other, a plurality of sets of stationary

contacts mounted upon the bottom and end walls of said recess, a corresponding number of bridging contactors slidably positioned upon the lower surface of said block and resiliently biased to a given relationship to the latter, means for substantially completely isolating each set of contacts and its associated contactor from the others, said means comprising barrier portions formed integrally with the bottom and end walls of said recess, said block having grooves formed in the corresponding surfaces thereof for overlapping engagement with the respective barrier portions in all positions of said parts, said recess having a series of adjacent cam-shaped grooves formed in a side wall thereof, a plunger slidably carried by said block and spring-biased laterally therefrom for cooperation with the walls of said grooves to normally insure a given positioning of said block with respect to said recess upon a predetermined degree of movement of the former, and manually operable means having a lost-motion driving connection with said block for effecting movement of the latter at will in opposite directions respectively.

2. In a multi-pole electric switch, in combination, a recessed molded insulating base, a molded insulating block slidably positioned within said recess for movement from one extreme position to the other, a plurality of sets of stationary contacts mounted upon the bottom and end walls of said recess, a corresponding number of bridging contactors slidably positioned upon the lower surface of said block and resiliently biased to a given relationship to the latter, means for substantially completely isolating each set of contacts and its associated contactor from the others, said means comprising barrier portions formed integrally with the bottom and end walls of said recess, said block having grooves formed in the corresponding surfaces thereof for overlapping engagement with the respective barrier portions in all positions of said parts, said recess having a series of adjacent cam-shaped grooves formed in a side wall thereof, a plunger slidably carried by said block and spring-biased laterally therefrom for cooperation with the walls of said grooves to normally insure a given positioning of said block with respect to said recess upon a predetermined degree of movement of the former, manually operable means having a lost-motion driving connection with said block for effecting movement of the latter at will in opposite directions respectively, and said contactors and said block having cooperating shoulders formed thereon to positively insure disengagement of the former from their associated contacts after a predetermined degree of movement of said block by said manual means.

3. In a multi-pole, double-throw electric switch, in combination, a recessed molded insulating base, a molded insulating block slidably positioned within said recess for movement from an intermediate "off" position to one or another of its "on" positions, a plurality of sets of stationary contacts positioned adjacent the bottom wall and the opposite end walls of said recess, a corresponding number of double-ended bridging contactors slidably positioned upon the lower surface of said block, said block having pairs of shoulders formed therein for cooperation with the ends of the respective contactors to limit the degree of movement of the latter in each direction relatively to said block, coiled compression springs interposed between each of said shoulders and the adjacent ends of said contactors to normally

bias the latter to a centered relationship to said block, means for substantially completely insulating each set of contacts and its associated contactor from an adjacent set, said means comprising a relatively low intermediate barrier portion and a set of relatively high end barrier portions formed integrally with the bottom and end walls of said recess, said block having grooves formed in the corresponding surfaces thereof for slidable overlapping engagement with the respective barrier portions in all positions of said parts, each side wall of said recess having a series of three adjacent V-shaped vertical grooves formed therein, said block having a pair of plungers slidably mounted therein and spring-biased outwardly therefrom for cooperation with the walls of said grooves to resiliently retain said block in any one of the three positions to which it may be moved, and manually operable means having a lost-motion driving connection with said block for effecting movement of the latter at will to any one of said three positions thereof.

4. In a multi-pole, double-throw electric switch, in combination, a recessed molded insulating base, a molded insulating block slidably positioned within said recess for movement from an intermediate "off" position to one or another of its "on" positions, a plurality of sets of stationary contacts positioned adjacent the bottom wall and the opposite end walls of said recess, a corresponding number of double-ended bridging contactors slidably positioned upon the lower surface of said block, said block having pairs of shoulders formed thereon for cooperation with the ends of the respective contactors to limit the degree of movement of the latter in each direction relatively to said block, coiled compression springs interposed between each of said shoulders and the adjacent ends of said contactors to normally bias the latter to a centered relationship to said block, means for substantially completely insulating each set of contacts and its associated contactor from an adjacent set, said means comprising a relatively low intermediate barrier portion and a set of relatively high end barrier portions formed integrally with the bottom and end walls of said recess, said block having grooves formed in the corresponding surfaces thereof for slidable overlapping engagement with the respective barrier portions in all positions of said parts, each side wall of said recess having a series of three adjacent V-shaped vertical grooves formed therein, said block having a pair of plungers slidably mounted therein and spring-biased outwardly therefrom for cooperation with the walls of said grooves to resiliently retain said block in any one of the three positions to which it may be moved, said block having a recess formed therein and opening to the upper surface thereof, and a lever pivotally supported relatively to said base, the lower end of said lever having a lost-motion driving connection with the walls of said last mentioned recess.

5. In a multi-pole, double-throw electric switch, in combination, a recessed molded insulating base, a molded insulating block slidably positioned within said recess for movement from an intermediate "off" position to one or another of its "on" positions, a plurality of sets of stationary contacts positioned adjacent the bottom wall and the opposite end walls of said recess, a corresponding number of double-ended bridging contactors slidably positioned upon the lower surface of said block, said block having pairs of shoulders formed thereon for cooperation with

the ends of the respective contactors to limit the degree of movement of the latter in each direction relatively to said block, coiled compression springs interposed between each of said shoulders and the adjacent ends of said contactors to normally bias the latter to a centered relationship to said block, means for substantially completely insulating each set of contacts and its associated contactor from an adjacent set, said means comprising a relatively low intermediate barrier portion and a set of relatively high end barrier portions formed integrally with the bottom and end walls of said recess, said block having grooves formed in the corresponding surfaces thereof for slidable overlapping engagement with the respective barrier portions in all positions of said parts, each side wall of said recess having a series of three adjacent V-shaped vertical grooves formed therein, said block having a pair of plungers slidably mounted therein and spring-biased outwardly therefrom for cooperation with the walls of said grooves to resiliently retain said block in any one of the three positions to which it may be moved, said block having a recess formed therein and opening to the upper surface thereof, a lever pivotally supported relatively to said base, the lower end of said lever having a lost-motion driving connection with the walls of said last mentioned recess, one contact of each of said sets having a resilient free end portion adapted for continuous slidable engagement with its associated contactor, and means including an insulating member overlying the upper end of said base and said block to restrain the latter against upward displacement from said first mentioned recess.

6. In a multi-pole, double-throw electric switch, in combination, a recessed molded insulating base, a molded insulating block slidably positioned within said recess for movement from an intermediate "off" position to one or another of its "on" positions, a plurality of sets of stationary contacts positioned adjacent the bottom wall and the opposite end walls of said recess, a corresponding number of double-ended bridging contactors slidably positioned upon the lower surface of said block, said block having pairs of shoulders formed thereon for cooperation with the ends of the respective contactors to limit the degree of movement of the latter in each direction relatively to said block, coiled compression springs interposed between each of said shoulders and the adjacent ends of said contactors to normally bias the latter to a centered relationship to said block, means for substantially completely insulating each set of contacts and its associated contactor from an adjacent set, said means comprising a relatively low intermediate barrier portion and a set of relatively high end barrier portions formed integrally with the bottom and end walls of said recess, said block having grooves formed in the corresponding surfaces thereof for slidable overlapping engagement with the respective barrier portions in all positions of said parts, each side wall of said recess having a series of three adjacent V-shaped vertical grooves formed therein, said block having a pair of plungers slidably mounted therein and spring-biased outwardly therefrom for cooperation with the walls of said grooves to resiliently retain said block in any one of the three positions to which it may be moved, said block having a recess formed therein and opening to the upper surface thereof, a lever pivotally supported relatively to said base, the lower end of said lever having a lost-motion

driving connection with the walls of said last mentioned recess, one contact of each of said sets having a resilient free end portion adapted for continuous slidable engagement with its associated contactor, means including an insulating member overlying the upper end of said base and said block to restrain the latter against upward displacement from said first mentioned recess, and each of said contacts having a wiring terminal member electrically connected thereto and accessible at the lower surface of said base.

7. In a multi-pole, double-throw electric switch, in combination, a recessed molded insulating base, a molded insulating block slidably positioned within said recess for movement from an intermediate "off" position to one or another of its "on" positions, a plurality of sets of stationary contacts positioned adjacent the bottom wall and the opposite end walls of said recess, a corresponding number of double-ended bridging contactors slidably positioned upon the lower surface of said block, said block having pairs of shoulders formed thereon for cooperation with the ends of the respective contactors to limit the degree of movement of the latter in each direction relatively to said block, coiled compression springs interposed between each of said shoulders and the adjacent ends of said contactors to normally bias the latter to a centered relationship to said block, means for substantially completely insulating each set of contacts and its associated contactor from an adjacent set, said means comprising a relatively low intermediate barrier portion and a set of relatively high end barrier portions formed integrally with the bottom and end walls of said recess, said block having grooves formed in the corresponding surfaces thereof for slidable overlapping engagement with the respective barrier portions in all positions of said parts, each side wall of said recess having a series of three adjacent V-shaped vertical grooves formed therein, said block having a pair of plungers slidably mounted therein and spring-biased outwardly therefrom for cooperation with the walls of said grooves to resiliently retain said block in any one of the three positions to which it may be moved, said block having a recess formed therein and opening to the upper surface thereof, a lever pivotally supported relatively to said base, the lower end of said lever having a lost-motion driving connection with the walls of said last mentioned recess, one contact of each of said sets having a resilient free end portion adapted for continuous slidable engagement with its associated contactor, means including an insulating member overlying the upper end of said base and said block to restrain the latter against upward displacement from said first mentioned recess, each of said contacts having a wiring terminal member electrically connected thereto and accessible at the lower surface of said base, and said lower surface of said base having barriers formed integrally therewith between each and all of said terminal members.

8. In a multi-pole switch of the character described, in combination, a molded insulating base of substantially rectangular contour, said base having a substantially rectangular recess formed therein and opening to the upper surface thereof, said recess having a plurality of sets of barrier portions formed integrally with the bottom and end walls thereof, a molded insulating block of substantially rectangular contour freely insertable into said recess to a position substantially flush with the upper end of the latter, said block

being so dimensioned as to afford a predetermined degree of sliding movement thereof in said plane, and said block having a plurality of sets of grooves in the bottom surface and the respective end surfaces thereof to respectively slidably accommodate the aforementioned barrier portions in all of the respective positions of said parts, whereby a plurality of compartments are provided in insulated relationship to each other, each of said compartments being adapted to house a set of stationary contacts and a bridging contactor to be associated therewith.

9. In a multi-pole switch of the character described, in combination, a molded insulating base of substantially rectangular contour, said base having a substantially rectangular recess formed therein and opening to the upper surface thereof, said recess having a plurality of sets of barrier portions formed integrally with the bottom and end walls thereof, a molded insulating block of substantially rectangular contour freely insertable into said recess to a position substantially flush with the upper end of the latter, said block being so dimensioned as to afford a predetermined degree of sliding movement thereof in said plane, said block having a plurality of sets of grooves in the bottom surface and the respective end surfaces thereof to respectively slidably accommodate the aforementioned barrier portions in all of the respective positions of said parts, whereby a plurality of compartments are provided in insulated relationship to each other, each of said compartments being adapted to house a set of stationary contacts and a bridging contactor to be associated therewith, each side wall of said recess having a plurality of substantially V-shaped vertical grooves formed therein and opening to the upper end of said base, and said block having a pair of insulating plungers slidably carried thereby and spring-biased outwardly therefrom, said plungers jointly cooperating with said grooves to yieldably urge said block to one or another of the positions predetermined therefor.

10. In a multi-pole switch of the character described, in combination, a molded insulating base of substantially rectangular contour, said base having a substantially rectangular recess formed therein and opening to the upper surface thereof, said recess having a plurality of sets of barrier portions formed integrally with the bottom and end walls thereof, a molded insulating block of substantially rectangular contour freely insertable into said recess to a position substantially flush with the upper end of the latter, said block being so dimensioned as to afford a predetermined degree of sliding movement thereof in said plane, said block having a plurality of sets of grooves in the bottom surface and the respective end surfaces thereof to respectively slidably accommodate the aforementioned barrier portions in all of the respective positions of said parts, whereby a plurality of compartments are provided in insulated relationship to each other, each of said compartments being adapted to house a set of stationary contacts and a bridging contactor to be associated therewith, each side wall of said recess having a plurality of substantially V-shaped vertical grooves formed therein and opening to the upper end of said base, and said block having a pair of insulating plungers slidably carried thereby and spring-biased outwardly therefrom, said plungers jointly cooperating with said grooves to yieldably urge said block to one or another of the positions predetermined

therefor, means comprising a manually operable lever pivotally supported relatively to said base, said block having a recess formed in the upper surface thereof, and the lower end of said lever having a lost-motion driving connection with the walls of said last mentioned recess.

11. In an electric switch, in combination, a recessed molded insulating base, a molded insulating block positioned and slidable within the recess in a substantially flush relationship to the upper surface of said base, said recess having one dimension of substantially greater length than the corresponding dimension of said block to permit a predetermined degree of movement of the latter from one extreme position to the other, a set of stationary contacts respectively located adjacent the bottom and end walls of said recess, a bridging contactor positioned upon the lower surface of said block, said block and said contactor being cooperatively formed to provide a predetermined degree of sliding lost motion therebetween, spring means interposed between said block and said contactor to normally bias the latter to a given position relatively to said block, one of said contacts having a continuous, resilient, slidable engagement with said contactor, said contactor being movable by said block into and out of engagement with another of said contacts, at least one wall of said recess having a plurality of adjacent V-shaped grooves formed therein, a spring pressed plunger carried by said block for cooperation with the walls of said grooves for definitely positioning said block and said contactor when the latter is in or out of engagement with said contact last mentioned, and means including a manually operable lever pivotally supported above said base, said lever having a lost motion driving connection with said block.

12. In an electric switch, in combination, a recessed molded insulating base, a molded insulating block slidably positioned within the recess in a substantially flush relationship to the upper surface of said base, said recess having one dimension of substantially greater length than the corresponding dimension of said block to permit a predetermined degree of movement of the latter from one extreme position to the other, a plurality of sets of stationary contacts respectively located adjacent the bottom and end walls of said recess, a corresponding number of double-ended bridging contactors positioned upon the lower surface of said block, said block and said contactors being cooperatively formed to provide a predetermined degree of sliding lost motion therebetween, coiled compression springs interposed between said block and certain of the ends of said contactors to normally bias the latter to given like positions relatively to said block, one contact of each set having a continuous, resilient, slidable engagement with its associated contactor, said contactors being movable jointly by said block into and out of engagement with another contact of each set, at least one side wall of said recess having a plurality of adjacent V-shaped grooves formed therein, a plunger carried by said block and spring-biased laterally therefrom for cooperation with the walls of said grooves for definitely positioning said block and said contactors when the latter are jointly in or out of engagement with the respective contacts last mentioned, and means including a manually operable lever having a pivot in fixed relationship to said base, the lower end of said lever having a lost motion driving connection with said block.

13. In an electric switch, in combination,

recessed molded insulating base, a molded insulating block slidably positioned within the recess in a substantially flush relationship to the upper surface of said base, said recess having one dimension of substantially greater length than the corresponding dimension of said block to permit a predetermined degree of movement of the latter from one extreme position to the other, a plurality of sets of stationary contacts respectively located adjacent the bottom and end walls of said recess, a corresponding number of double-ended bridging contactors positioned upon the lower surface of said block, said block and said contactors being cooperatively formed to provide a predetermined degree of sliding lost motion therebetween, coiled compression springs interposed between said block and certain of the ends of said contactors to normally bias the latter to given like positions relatively to said block, one contact of each set having a continuous, resilient, slidable engagement with its associated contactor, said contactors being movable jointly by said block into and out of engagement with another contact of each set, at least one side wall of said recess having a plurality of adjacent V-shaped grooves formed therein, a plunger carried by said block and spring-biased laterally therefrom for cooperation with the walls of said grooves for definitely positioning said block and said contactors when the latter are jointly in or out of engagement with the respective contacts last mentioned, means including a manually operable lever having a pivot in fixed relationship to said base, the lower end of said lever having a lost motion driving connection with said block, said recess having barrier portions formed integrally with the bottom and end walls thereof between each of said sets of contacts, and said block having grooves formed in the bottom and end surfaces thereof between each of said contactors to accommodate said barrier portions in all positions of said block, whereby substantially closed arcing chambers are provided for each set of contacts and the contactors respectively associated therewith.

14. In an electric switch, in combination, a molded insulating base having a substantially rectangular recess formed therein and opening to the upper surface thereof, a set of stationary contacts located within said recess, one contact being positioned adjacent and in parallel relation to an end wall of said recess, another contact being resilient and having a curved free end portion projecting upwardly a substantial distance from the bottom wall of said recess, a molded insulating block positioned within said recess and guided by the side walls of the latter for movement in a plane parallel to said bottom wall, a contactor having a relatively long flat intermediate portion with relatively short integral arms upstanding therefrom being positioned upon the lower surface of said block and having a predetermined degree of lost motion with respect thereto, a pair of coiled compression springs interposed between the respective contactor arms and abutments formed on said block to normally bias said contactor to a centered position relatively to said block, the free end portion of said resilient contact being continuously engaged with said contactor, a plunger carried by said block and spring-biased toward a side wall of said recess, said side wall having cam-shaped vertical grooves formed therein adjacent to each other for cooperation with said plunger to resist sliding movement of said block from

each of a plurality of predetermined positions to another, means including a plate overlying said recess to restrain said block against upward displacement, and manually operable means for effecting the aforementioned movements of said block.

15. In an electric switch, in combination, a molded insulating base having a substantially rectangular recess formed therein and opening to the upper surface thereof, a set of stationary contacts located within said recess, one contact being positioned adjacent and in parallel relation to an end wall of said recess, another contact being resilient and having a curved free end portion projecting upwardly a substantial distance from the bottom wall of said recess, a molded insulating block positioned within said recess and guided by the side walls of the latter for movement in a plane parallel to said bottom wall, a contactor having a relatively long flat intermediate portion with relatively short integral arms upstanding therefrom being positioned upon the lower surface of said block and having a predetermined degree of lost motion with respect thereto, a pair of coiled compression springs interposed between the respective contactor arms and abutments formed on said block to normally bias said contactor to a centered position relatively to said block, the free end portion of said resilient contact being continuously engaged with said contactor, a plunger carried by said block and spring-biased toward a side wall of said recess, said side wall having cam-shaped vertical grooves formed therein adjacent to each other for cooperation with said plunger to resist sliding movement of said block from each of a plurality of predetermined positions to another, means including a plate overlying said recess to restrain said block against upward displacement, manually operable means for effecting the aforementioned movements of said block, and said spring-biased plunger acting to insure movement of said block and said contactor to one or another of their predetermined positions upon release of said manually operable means under all conditions.

16. In an electric switch, in combination, a molded insulating base having a relatively deep substantially rectangular recess formed therein and opening to the upper end thereof, a molded insulating block positioned within said recess in a relationship substantially flush with the upper surface of said base, at least one contactor carried by said block at the lower end of the latter, said contactor having a resilient connection with said block to afford a predetermined degree of sliding lost motion therebetween, a set of stationary contacts positioned within said recess, at least one of said contacts having a portion upstanding from the bottom wall of said recess adjacent and in parallel relationship to an end wall of the latter, another of said contacts having an upwardly extending resilient arm continuously slidably engaged with said contactor, said contactor having a portion parallel to said portion of the first mentioned contact and movable into and out of engagement with the latter, means for effecting such movements of said contactor, said last mentioned means including manually operable means for effecting corresponding movements of said block, and means including a spring-pressed plunger carried by said block and a plurality of V-shaped grooves formed adjacent each other in said recess for cooperation with said plunger to insure movement of said block and said contactor to one or another of the predetermined positions

thereof upon a given degree of movement of said block by said manually operable means in each direction respectively.

17. In an electric switch, in combination, a molded insulating base having a relatively deep substantially rectangular recess formed therein and opening to the upper end thereof, a molded insulating block positioned within said recess in a relationship substantially flush with the upper surface of said base, at least one contactor carried by said block at the lower end of the latter, said contactor having a resilient connection with said block to afford a predetermined degree of sliding lost motion therebetween, a set of stationary contacts positioned within said recess, at least one of said contacts having a portion upstanding from the bottom wall of said recess adjacent and in parallel relationship to an end wall of the latter, another of said contacts having an upwardly extending resilient arm continuously slidably engaged with said contactor, said contactor having a portion parallel to said portion of the first mentioned contact and movable into and out of engagement with the latter, means for effecting such movements of said contactor, said last mentioned means including manually operable means for effecting corresponding movements of said block, means including a spring-pressed plunger carried by said block and a plurality of V-shaped grooves formed adjacent each other in said recess for cooperation with said plunger to insure movement of said block and said contactor to one or another of the predetermined positions thereof upon a given degree of movement of said block by said manually operable means in each direction respectively, and means including a coiled spring interposed between said block and said manually operable means to insure proper follow-up positioning of the latter upon manual release thereof, whereby the condition of the controlled circuit is indicated.

18. As an article of manufacture, a molded insulating block of substantially rectangular contour, said block having a recess formed therein centrally thereof, said recess having a flared end opening to the upper surface of said block, a coiled compression spring positioned within said recess to provide a resilient abutment for the lower end of a manually operable member of suitable form, a contactor slidably positioned upon the lower surface of said block, said contactor having end portions bent upwardly at substantially right angles thereto, said block having vertical shoulders offset inwardly from opposite ends thereof for engagement selectively by the respective ends of said contactor to limit the degree of sliding movement of the latter in each direction relatively to said block, said block also having vertical shoulders offset inwardly from the respective shoulders aforementioned, and a pair of coiled compression springs interposed between said last mentioned shoulders and the respective ends of said contactor to normally insure substantially centered position of the latter relatively to said block.

19. As an article of manufacture, a molded insulating block of substantially rectangular contour, said block having a recess formed therein centrally thereof, said recess having a flared end opening to the upper surface of said block, a coiled compression spring positioned within said recess to provide a resilient abutment for the lower end of a manually operable member of suitable form, a contactor slidably positioned upon the lower surface of said block, said contactor

having end portions bent upwardly at substantially right angles thereto, said block having vertical shoulders offset inwardly from opposite ends thereof for engagement selectively by the respective ends of said contactor to limit the degree of sliding movement of the latter in each direction relatively to said block, said block also having vertical shoulders offset inwardly from the respective shoulders aforementioned, and a coiled compression spring interposed between at least one of said last mentioned shoulders and the adjacent end of said contactor to normally insure a predetermined position of the latter relatively to said block.

15 20. As an article of manufacture, a molded insulating block of substantially rectangular contour, said block having a substantially cylindrical recess formed therein centrally thereof, said recess having a flared end opening to the upper surface of said block, a coiled compression spring positioned within said recess to act as a resilient abutment for the lower end of a pivoted lever of suitable form, a plurality of like bridging contactors slidably positioned in parallel spaced relationship to each other upon the lower surface of said block, each contactor having opposite end portions thereof bent upwardly at substantially right angles thereto, said block having pairs of vertical shoulders offset inwardly from opposite ends thereof, the shoulders of said pairs being adapted for engagement selectively by the respective ends of said contactors to limit the degree of sliding movement of the latter in each direction relatively to said block, said block also having pairs of relatively smaller vertical shoulders offset inwardly from the shoulders of the respective pairs aforementioned, and a plurality of coiled compression springs each interposed between one of the last mentioned shoulders and an adjacent end of a contactor.

21. As an article of manufacture, a molded insulating block of substantially rectangular contour, said block having a substantially cylindrical recess formed therein centrally thereof, said recess having a flared end opening to the upper surface of said block, a coiled compression spring positioned within said recess to act as a resilient abutment for the lower end of a pivoted lever of suitable form, a plurality of like bridging contactors slidably positioned in parallel spaced relationship to each other upon the lower surface of said block, each contactor having opposite end portions thereof bent upwardly at substantially right angles thereto, said block having pairs of vertical shoulders offset inwardly from opposite ends thereof, the shoulders of said pairs being adapted for engagement selectively by the respective ends of said contactors to limit the degree of sliding movement of the latter in each direction relatively to said block, said block also having pairs of relatively smaller vertical shoulders offset inwardly from the shoulders of the respective pairs aforementioned, and a corresponding number of coiled compression springs respectively interposed between each of the last mentioned shoulders and an adjacent end of a contactor, to thereby normally insure substantially centered positioning of each of said contactors relatively to said block.

22. As an article of manufacture, a molded insulating block of substantially rectangular contour, said block having a substantially cylindrical recess formed therein centrally thereof, said recess having a flared end opening to the upper surface of said block, a coiled compression spring

positioned within said recess to act as a resilient abutment for the lower end of a pivoted lever of suitable form, a plurality of like bridging contactors slidably positioned in parallel spaced relationship to each other upon the lower surface of said block, each contactor having opposite end portions thereof bent upwardly at substantially right angles thereto, said block having pairs of vertical shoulders offset inwardly from opposite ends thereof, the shoulders of said pairs being adapted for engagement selectively by the respective ends of said contactors to limit the degree of sliding movement of the latter in each direction relatively to said block, said block also having pairs of relatively smaller vertical shoulders offset inwardly from the shoulders of the respective pairs aforementioned, a corresponding number of coiled compression springs respectively interposed between each of the last mentioned shoulders and an adjacent end of a contactor, to thereby normally insure substantially centered positioning of each of said contactors relatively to said block, and said block having grooves formed in the bottom and side surfaces thereof between each of said contactors for sliding and sealing engagement with barriers formed upon a suitable insulating base.

23. In an electric switch, in combination, a molded insulating base having a substantially rectangular recess formed therein and opening to the upper surface thereof, a molded insulating block of substantially rectangular contour, said block being of a size to fit between and be guided by the side walls of said recess, said recess being of a length to permit a predetermined degree of movement of said block in a straight line between opposite extreme positions thereof, at least one set of stationary contacts positioned adjacent the bottom and end walls of said recess, a contactor having a flat portion thereof slidable upon the bottom surface of said block, said contactor having end portions bent in a like direction into overlapping relationship to said block, said block having shoulders formed thereon for engagement by the respective end portions of said contactor to limit the degree of sliding movement of the latter relatively to said block, a coiled compression spring interposed between one of said shoulders and one end portion of said contactor to normally bias the latter to a given position relatively to said block, said last mentioned end portion of said contactor being adapted for movement into and out of engagement with one of the contacts of said set as an incident to corresponding movements of said block, another contact having a resilient portion affording a continuous sliding engagement thereof with the flat portion of said contactor, said spring acting upon movement of said block to one extreme position to afford a predetermined degree of pressure of said contactor against said first mentioned contact and to prevent bouncing of said contactor as an incident to such engagement, at least one plunger carried by said block and spring-biased outwardly with respect thereto, and a corresponding number of sets of grooves formed in a wall or walls of said recess for cooperation therewith to resiliently retain said block and said contactor in any one of a number of predetermined positions to which the same may be moved.

24. In an electronic switch, in combination, a molded insulating base having a substantially rectangular recess formed therein and opening to the upper surface thereof, a molded insulating block of substantially rectangular contour,

said block being of a size to fit between and be guided by the side walls of said recess, said recess being of a length to permit a predetermined degree of movement of said block in a straight line between opposite extreme positions thereof, at least one set of stationary contacts positioned adjacent the bottom and end walls of said recess, a contactor having a flat portion thereof slidable upon the bottom surface of said block, said contactor having end portions bent in a like direction into overlapping relationship to said block, said block having shoulders formed thereon for engagement by the respective end portions of said contactor to limit the degree of sliding movement of the latter relatively to said block, a coiled compression spring interposed between one of said shoulders and one end portion of said contactor to normally bias the latter to a given position relatively to said block, said last mentioned end portion of said contactor being adapted for movement into and out of engagement with one of the contacts of said set as an incident to a corresponding movement of said block, another contact having a resilient portion affording a continuous sliding engagement thereof with the flat portion of said contactor, said spring acting upon movement of said block to one extreme position to afford a predetermined degree of pressure of said contactor against said first mentioned contact and to prevent bouncing of said contactor as an incident to such engagement, at least one plunger carried by said block and spring-biased outwardly with respect thereto, a corresponding number of sets of grooves formed in a wall or walls of said recess for cooperation therewith to resiliently retain said block and said contactor in any one of a number of predetermined positions to which the same may be moved, said block having a substantially centrally located recess formed in the top surface thereof, a coiled compression spring within said last mentioned recess, a pivoted lever having one end portion loosely positioned within said recess and engaged with said spring to provide for movement of said block to said predetermined positions upon substantially corresponding movement of said lever.

25. In an electric switch, in combination, a recessed molded insulating base, a molded insulating block positioned and slidable within the recess in a substantially flush relationship to the upper surface of said base, said recess having one dimension of substantially greater length than the corresponding dimension of said block to permit a predetermined degree of movement of the latter from one extreme position to the other, a set of stationary contacts respectively located adjacent the bottom and end walls of said recess, a bridging contactor positioned upon the lower surface of said block, said block and said contactor having cooperating pairs of shoulders formed thereon to afford a predetermined degree of sliding lost motion therebetween, spring means interposed between said block and said contactor to normally bias the latter to a given position relatively to said block, one of said contacts having a continuous, resilient, slidably engageable portion with said contactor, said contactor being movable by said block into and out of engagement with another of said contacts, at least one wall of said recess having a plurality of adjacent V-shaped grooves formed therein, a spring pressed plunger carried by said block for cooperation with walls of said grooves for normally definitely positioning said block and

said contactor when the latter is in or out of engagement with said contact last mentioned, means including a manually operable lever pivotally supported relatively to said base, said lever having a lost motion driving connection with said block, said block and said base having pairs of alined recesses formed therein and opening toward each other at the adjacent ends thereof, and a plurality of coiled springs interposed under a predetermined degree of compression between the end walls of certain of said alined recesses, said last mentioned springs acting to insure return of said block and said contactor to a predetermined position upon release of said lever after manual movement of the latter in a given direction.

26. In a multi-pole electric switch, in combination, a recessed insulating base, a contactor supporting means slidably positioned within said recess, a plurality of sets of stationary contacts mounted upon the insulating base, a corresponding number of bridging contactors positioned upon the contactor supporting means, means for substantially completely isolating each set of contacts and its associated contactor from the others, and manually operable means having a driving connection with said contact or supporting means for effecting movement of the latter at will in opposite directions respectively.

27. In a multi-pole electric switch, in combination, a recessed insulating base, a contactor supporting means slidably positioned within said recess, a plurality of sets of stationary contacts mounted upon the insulating base, a corresponding number of bridging contactors positioned upon the contactor supporting means, means for substantially completely isolating each set of contacts and its associated contactor from the others, manually operable means having a driving connection with said contactor supporting means for effecting movement of the latter at will in opposite directions respectively, said recess having cam-shaped elements formed therein, and a plunger carried by said contactor supporting means and spring-biased for cooperation with said cam-shaped elements to normally insure a given positioning of said contactor supporting means with respect to said recess upon a predetermined degree of movement of the former.

28. In a multi-pole electric switch, in combination, a recessed insulating base, a contactor supporting means slidably positioned within said recess, a plurality of sets of stationary contacts mounted upon the insulating base, a correspond-

ing number of bridging contactors positioned upon the contactor supporting means, means for substantially completely isolating each set of contacts and its associated contactor from the other, said last mentioned means comprising barrier portions formed integrally with the walls of said recess, said contactor supporting means having grooves formed in the corresponding surfaces thereof for overlapping engagement with the respective barrier portions in all positions of said contactor supporting means, and manually operable means having a driving connection with said contactor supporting means for effecting movement of the latter at will in opposite directions respectively.

29. In a multi-pole electric switch, in combination, a recessed insulating base, a contactor supporting means slidably positioned within said recess, a plurality of sets of stationary contacts mounted upon the insulating base, a corresponding number of bridging contactors positioned upon the contactor supporting means, means for substantially completely isolating each set of contacts and its associated contactor from the others, manually operable means having a driving connection with said contactor supporting means for effecting movement of the latter at will in opposite directions respectively, said recess having cam-shaped elements formed therein, a plunger carried by said contactor supporting means and spring-biased for cooperation with said cam-shaped elements to normally insure a given positioning of said contactor supporting means with respect to said recess upon a predetermined degree of movement of the former, said isolating means comprising barrier portions formed integrally with the walls of said recess, and said contactor supporting means having grooves formed in the corresponding surfaces thereof for overlapping engagement with the respective barrier portions in all positions of said contactor supporting means.
